UNITED STATES PATENT OFFICE.

MATTHEW CHAPMAN, OF GREENFIELD, MASSACHUSETTS.

DESIGN FOR A KNIFE-HANDLE.

Specification forming part of Design No. 5,609, dated March 5, 187.

Specification describing a new and original Design for Handles of Knives and Forks, invented by MATTHEW CHAPMAN, of Greenfield, in the county of Franklin and State of Massachusetts.

Figure 1 represents a side view of a knife having my new design of handle. Fig. 2 is a transverse section of the same on the line *c c*, Fig. 1.

Similar letters of reference indicate corresponding parts.

This invention relates to a new form of handle for knives and forks; and consists in enlarging the same at or near the middle and beveling it at the corners.

A in the drawing represents the handle of a knife or fork. It is made of wood or other material, with an enlargement or swell in the middle, as shown. The corners of the handle are beveled, as shown at *a a* in Fig. 2. This form applies to carving, butcher, and table knives, and other kinds of cutlery.

I claim as my invention—

The design for the beveled handle having the swell in the middle, as shown.

MATTHEW CHAPMAN.
